PORTABLE VENTILATING AND COOLING UNIT

Samuel L. McNair, Whitman, Mass.

Application May 31, 1956, Serial No. 41,702

Term of patent 7 years

(Cl. D62—4)

Fig. 1.

Fig. 2.

Fig. 3.

Fig. 4.

Fig. 1 is a front elevational view,
Fig. 2 is a side elevational view,

Fig. 3 is a top plan view, and

Fig. 4 is a front perspective view of a portable ventilating and cooling unit embodying my new design.

The rear of my device, not shown, is similar to the front.

I claim:

The ornamental design for a portable ventilating and cooling unit, substantially as shown and described.
